CONDENSATION VACUUM PUMP

Frank Edmund Bancroft, Sale, and Charles Walter Miller, Roundhay, Leeds, England, assignors, by mesne assignments, to General Electric Company, a corporation of New York

Application March 8, 1940, Serial No. 322,936
In Great Britain March 18, 1939

3 Claims. (Cl. 230—101)

This invention relates to condensation or diffusion vacuum pumps of the kind designed and constructed for operation with an organic liquid, for example the oil which is known as "Apiezon" oil (Apiezon being a registered trademark), or other organic liquids having a vapour pressure considerably lower than that of mercury.

The invention has for its object to provide improvements in such pumps whereby to improve the backing pressure characteristic or, in other words, the fore-vacuum pressure against which the pump may be capable of operating.

In considering such pumps it is known that, in order for the jet to be capable of operating against a high fore-vacuum pressure, the density of the vapour in the space immediately next to the jet towards the fore-vacuum side of the pump should be as high as possible. However, from the jet is obviously limited by such factors as the temperature and superficial area of the boiler, and the vapour pressure of the pump filling at the temperature of the boiler. It is also known that increase of the boiler temperature and of the vapour pressure of the pump filling causes an increase in the maximum fore-vacuum pressure against which the jet will operate. Moreover, in the case of multi-stage pumps, such factors as the vapour pressure of the filling and the boiler temperature are restricted by considerations of the ultimate vacuum pressure which it is desired should be obtained with the jet nearest the high-vacuum end or part of the pump.

It is thus apparent that the backing pressure characteristic of any given pump can be improved only to a limited extent by variation of the pump filling and boiler temperature. Moreover, even when these factors have been selected at their optimum value it is desirable that further increase in the fore-vacuum pressure against which the pump will operate should be obtained.

With the above and other considerations in view it is proposed according to the present invention, in a pump of the kind specified to provide a baffle between the hot vapour uptake pipe or duct and the condenser surface so as to constrict the space into which is fed the vapour from the jet to the fore-vacuum pipe or outlet, or, in other words, between the jet and the fore-vacuum pipe or outlet in the case of a single stage pump or, in the case of a multi-stage pump, between the high backing pressure

jet and the fore-vacuum outlet. With such provision, since the total number of vapour molecules issuing from the jet is to a first approximation fixed by the factors aforementioned, the density of such molecules in the space will be increased and thus the backing pressure characteristic of the pump improved. Other advantages will hereinafter appear.

Conveniently, in the case of a vertical tubular pump the baffle referred to may be in the form of a thin-walled skirt surrounding and spaced from the uptake pipe and attached to the latter adjacent the jet and extending from the latter beyond the fore-vacuum outlet.

10 Thus, for example, in applying the invention to pumps of the construction disclosed in the specification of British Patent No. 346,293, the baffle may be in the form of a depending skirt surrounding the uptake pipe wholly across the mouth of the fore-vacuum pipe, being arranged to extend from a point on the uptake pipe adjacent the cowl to a point appreciably below the mouth of the fore-vacuum pipe; with this provision the baffles which were secured to the uptake pipe in the aforesaid specification so as to extend to within a short distance from the pump body below the fore-vacuum pipe may be omitted.

15 In applying the invention to a multi-jet pump having a single uptake pipe or a plurality of respective uptake pipes such as disclosed in the specification of U. S. application Serial No. 313,390, filed January 11, 1940, the baffle may be in the form of a skirt surrounding the uptake pipe or the outer uptake pipe and extending from beneath the lowermost jet downwards wholly across the mouth of the fore-vacuum pipe so as to constrict the space below the high backing pressure jet as required.

20 It is preferable to form the baffle skirt with its lower end flared or expanded outwardly so as to extend to within a very small distance from the pump body below the fore-vacuum outlet whereby the baffle also acts to prevent or otherwise minimise streaming from the boiler at the lower end of the uptake pipe and thus to obviate the necessity for the provision of other baffles secured to the lower end of the uptake pipe for this purpose.

25 By the use of a thin-walled baffle it will be appreciated that it will assume a temperature intermediate between that of the uptake pipe and that of the condensing surface; it will therefore be acting in some measure as a shield conserving heat in the uptake pipe, whilst in the

region of the fore-vacuum pipe or aperture the baffle will assist in the condensation of the vapour travelling down from the jet through the vapour reception space.

To enable the invention to be more fully understood two arrangements thereof will now be described by way of example with reference to Figs. 1 and 2 of the accompanying drawing, showing in sectional elevation two arrangements of pump to which the invention is applied, like reference numerals being used in both figures where applicable.

In the accompanying drawing at 1 is shown the boiler space for the organic liquid and at 2 an enclosure for an electric or other heater for the boiler 1. At 3 in Fig. 1 is shown a single vapour uptake pipe supplying at its upper end (not shown) a high vacuum jet which may be generally similar to the high vacuum jet 4 shown in Fig. 2.

In Fig. 1 at 5 is shown a cowl providing a jet 6 which is in tandem with the upper jet (not shown) and which is supplied with vapour through perforations 7 in the common uptake tube 3.

At 8 is shown the condenser surface, cooled by the circulation of fluid in the jacket 9. At 10 is shown the fore-vacuum pipe which is connected to the main pump body or casing at a place beneath the jacket 9.

In the arrangement shown in Fig. 2 there are two uptake pipes 3 and 3a respectively for the upper jet 4 and the lower jet 6. At 11 in Fig. 2 is shown a sleeve or liner which per se forms the subject matter of aforesaid U. S. application Serial No. 313,390.

In accordance with the present invention the vapour reception space beneath the lower jet 6, in either of the illustrated arrangements, is restricted by means of the baffle skirt 12 which, as will be seen extends from the region of the jet 6 in the form of a cylindrical tube spaced away as at 13 from the uptake tube 3 and extending downwards beyond the mouth of the fore-vacuum pipe 10. Preferably the lower end of the baffle skirt 12 is outwardly flared as shown at 14, for the purpose hereinbefore indicated.

The baffle skirt 12 is preferably supported and centred in position by means of spacing pins 15 extending through holes in the baffle and bearing at their inner ends on the uptake pipe 3 and bearing at their outer ends against the condenser surface 8. Preferably the baffle skirt and the pins 15 or any other means for supporting it from the uptake pipe 3 are constructed of a material having a relatively low thermal conductivity as for example mild steel or copper-nickel alloy so that said baffle skirt and supporting means are in general maintained at a temperature below that of the uptake pipe.

The invention has been found in practice particularly advantageous in the high speed multi-stage pump illustrated in Fig. 2 and described in the specification of the aforesaid U. S. appli-

cation Serial No. 313,390. In such a pump, in the absence of the baffle skirt 12, the lower jet 6 was capable of operating against a fore-vacuum pressure of approximately 340μ when using a pump filling of "Aplezon" oil "B" ("Aplezon" being a registered trade-mark) and with a heater wattage of 600. When the baffle skirt 12 was added the pump was capable of operating against a backing pressure up to 420μ or more.

With the arrangement shown in Fig. 2 it has also been found that the speed of the jet 6 can be increased by removing from the upper end of the sleeve or liner 11 the part thereof indicated by the dotted lines 16 so that the flaring at the upper end of said sleeve or liner is as shown in full lines.

We claim:

1. A diffusion pump including a pump casing providing internal condensing surfaces, a vapor source within the casing, a vapor duct leading upwardly from the said source, a pumping jet supplied with vapor from the said duct and so directed that the discharged vapors are projected downwardly against the condensing surfaces of the pump casing, a fore-vacuum pipe communicating with the interior of the pump casing at a point materially below the said jet and a baffle surrounding the said vapor duct and extending generally parallel thereto for a substantial portion of its length, the spacing between the said baffle and the said condensing surfaces being less than about half the spacing between the condensing surfaces and the vapor duct, whereby the passage between the vapor jet and the fore-vacuum pipe is materially restricted by the presence of the baffle.

2. A diffusion pump comprising a pump casing providing internal condensing surfaces, a vapor source within the casing, a vapor duct leading upwardly from the said source, a pumping jet supplied with vapor from the said duct and directed downwardly in such fashion that the discharged vapors are projected against the condensing surfaces of the pump casing, a fore-vacuum pipe connecting with the interior of the pump casing at a point materially below the said jet, and a baffle surrounding the said vapor duct in a region extending from the vapor jet to a point below the said point of connection of the fore-vacuum pipe, the spacing between the said baffle and the said condensing surfaces being less than about half the spacing between the condensing surfaces and the vapor duct, whereby the passage between the vapor jet and the said pipe is materially restricted by the presence of the baffle.

3. A diffusion pump according to claim 2 wherein the end of the baffle which extends below the point of connection of the fore-vacuum pipe is flared outwardly so as to extend close to the wall of the pump casing.
